Filed Dec. 11, 1961, Ser. No. 67,855

Term of patent 7 years

(Cl. D13—1)

F I G. 2

F I G. 3

F I G. 4

FIG. 1 is an enlarged perspective view of a portable, folding shelter for use as a chapel or the like showing my new design as it is seen in the fully open position thereof;

FIG. 2 is a perspective view of my portable and folding chapel as it is seen in the fully closed position thereof;

FIG. 3 is a perspective view thereof with the side wings open; and

FIG. 4 is a perspective view thereof corresponding to FIG. 1 and showing my new design in the fully open position thereof.

The undisclosed rear center panel is substantially like the front center panel except for the center table.

I claim:

The ornamental design for a portable, folding shelter for use as a chapel or the like substantially as shown and described.
